UNITED STATES PATENT OFFICE.

FREDERICK W. TAYLOR, OF ST. JOHNSBURY, VERMONT, ASSIGNOR TO
THE E. & T. FAIRBANKS & CO., OF SAME PLACE.

REGISTERING-BEAM FOR SCALES.

SPECIFICATION forming part of Letters Patent No. 684,132, dated October 8, 1901.

Application filed May 25, 1901. Serial No. 61,970. (No model.)

To all whom it may concern:

Be it known that I, FREDERICK W. TAYLOR, a citizen of the United States, residing at St. Johnsbury, in the county of Caledonia, State 5 of Vermont, have invented certain new and useful Improvements in Registering-Beams for Weighing-Scales, of which the following is a description, reference being had to the accompanying drawings and to the letters of 10 reference marked thereon.

The present invention relates to an improvement in weighing-scales of the type known as "printing or registering beams," as illustrated, for example, in the patent 15 granted Henry Fairbanks January 18, 1898, No. 597,640; and the object of the invention is to provide a construction of poise adapted for use with a continuous-strip ticket or with an ordinary ticket, the advantage in the use 20 of a continuous ticket being that the record of an entire day's weighing may be kept on one strip or ticket instead of requiring separate tickets for each load weighed.

The invention therefore consists in the matter 25 hereinafter described, and referred to in the appended claims.

The invention is illustrated in the accompanying drawings, in which—

Figure 1 is a perspective view, partly in section, of a portion of a weighing-scale of the 30 type referred to embodying my invention. Fig. 2 is a cross-section of the same. Fig. 3 is a plan view of a portion of a continuous ticket which I propose to use, and Fig. 4 is a 35 detail view of a separate ticket.

In the drawings, *f* represents the poise sliding on the beam *B*, which is of the usual construction employed in this type of scale. The poise slide or slides are of the usual construction, and the ticket *e* is adapted to be impressed against the face of the type on the beam and poise-slides in the usual way. The shell of the poise at the rear is provided with a slot registering with the slot in front, in 40 which the ticket is inserted, so that a continuous ticket *e* may be passed through the same and each section thereof, *e'*, impressed in the

usual manner. This opening *a* may be closed by a sliding plate *d*, having slots through which pass screws *i*, a thumb-screw *b* being 50 provided to manipulate the plate *d* up and down. If it is desired to use the continuous strip or ticket, the slide *d* is raised, leaving the opening *a* free for the passage of the ticket, which has cross or division lines at suitable 55 intervals, so that when a cross-line is flush with the face of the poise the impression will come at the proper place on the ticket. If, however, it is desired to print upon the separate sections or tickets *e'*, the screw *b* is 60 loosened, the plate *d* lowered across the opening *a*, and it thus acts as a stop or gage for the end of the ticket. The continuous strip or ticket is shown in Fig. 3 and a separate section thereof or ticket *e'* in Fig. 4. Each 65 section is properly ruled for the date, gross, tare, and net weight in the usual manner.

Having thus described my invention, what I claim as new, and desire to secure by Letters Patent, is—

1. In a printing or registering beam-scale, a beam, a poise sliding thereon, having an opening through the rear portion through which a continuous strip or ticket may pass, and a movable slide adapted to close said opening; substantially as described.

2. In a printing or registering beam-scale, a beam, a poise sliding thereon having an opening through the rear portion through which a continuous strip or ticket may pass, 80 and a sliding plate supported and guided vertically on the rear shell of the poise; substantially as described.

3. In a printing or registering beam-scale, a beam, a poise sliding thereon, and a stop 85 adjustably supported on the rear shell of the poise, against which the ticket may abut; substantially as described.

In testimony whereof I affix my signature in presence of two witnesses.

FREDERICK W. TAYLOR.
